UNITED STATES PATENT OFFICE

LOUIS BURKE, OF NEW YORK, N. Y., ASSIGNOR TO REYNOLDS WATCH CORPORATION, OF NEW YORK, N. Y., A CORPORATION OF DELAWARE

SELF-WINDING TIMEPIECE

Application filed July 26, 1929. Serial No. 381,146.

This invention relates to self-winding timepieces. It relates more particularly to self-winding watches adapted to be wound by the motion of the body of the wearer. It relates 5 still more particularly to an improved means for preventing over-winding of self-winding timepieces.

Among the objects of the invention are the provision of a compact self-winding time- 10 piece which will function more reliably than timepieces of such nature heretofore known with a minimum of wear, and the provision of improved over-winding mechanism.

Various types of self-winding timepieces 15 have heretofore been known which have been provided with mechanism intended to prevent over-winding thereof. Such over-winding mechanism, however, has not been generally satisfactory because of its unreliability and because of strain occasioned the 20 parts when the over-winding mechanism comes into action.

I provide a self-winding timepiece comprising a pendulum, a spring arbor rotatable 25 upon oscillation of the pendulum, a lateral extension connected with the arbor, and means operable by such extension upon rotation of the arbor to stop the pendulum when the timepiece is sufficiently wound. I 30 further provide a self-winding timepiece comprising a pendulum, winding means operated thereby, a Geneva movement connected with the winding means, and stop means controlled by the Geneva movement for preventing over-winding of the timepiece.

Other objects and advantages of the invention will become apparent as the following description of a present preferred embodiment 40 thereof proceeds.

In the accompanying drawings, I have shown a present preferred embodiment of the invention, wherein

Figure 1 is a plan view of a timepiece; 45 Figure 2 is a plan view to enlarged scale of a portion of the mechanism shown in Figure 1;

Figure 3 is a cross section taken on the line III—III of Figure 2;

50 Figure 4 is a cross section through the time-

piece taken substantially at right angles to that of Figure 3;

Figure 5 is a cross section similar to Figure 4, but showing the parts in a different position, and

Figure 6 is a cross section to smaller scale through a completed timepiece.

Referring more particularly to the drawings, reference numeral 2 designates a case in which is centrally pivoted at 3 a pendulum 4. The pendulum is provided with anti-friction rollers 5 adapted to ride on portions of the case to maintain the pendulum in proper position while in use and also to reduce the friction of the movement. The case 2 is provided with a base plate 6, to which is connected the timepiece movement, a dial 7 being painted on the outside of the base plate. A front bezel 8 is screwed to the case and holds a crystal 9. A central post 10 carries the hands 11 and 12, respectively. A detachable snap closure 13 is provided for the back of the timepiece, the anti-friction rollers 5 of the pendulum being adapted to roll against the closure 13 when the latter is in place. Thus, regardless of the position of the watch, the anti-friction rollers 5 are always in contact either with the base plate 6 or with the snap closure 13. The clearance between the anti-friction rollers 5 and the closure 13 is exaggerated in Figure 6. This clearance is actually only a few thousandths of an inch, or sufficient to permit removal and replacement of the snap closure 13 without causing binding of the pendulum.

Keyed to the post 10 is a bevel gear 14. Mounted in suitable bearings 15 and 16 connected to the base plate 6 is a setting shaft 17 having a bevel pinion 18 meshing with the gear 14. Keyed to the opposite end of the shaft 17 is a setting wheel 19 by which the watch may be set. The shaft 17 is always positively geared to the hands of the watch through the pinion 18 and gear 14, so that the setting wheel 19 always rotates with the hands, thus eliminating any clutch connection between the setting wheel and the hands. The setting wheel is readily accessible by removing the front bezel 8.

At the extremities of its movement, the 100

pendulum 4 strikes against stops 20 which are resiliently mounted in the frame against coil springs 21. This relieves the pendulum and connected mechanism of any jars or jolts 5 at the extremities of its stroke.

Loosely mounted on the pivot 3 is a gear 22. Pivoted to the pendulum at 23 is a pawl 24 resiliently urged into engagement with the teeth of the gear 22 by a spring 25. Meshing 10 with the gear 22 is a second gear 26 keyed to a shaft 27 to which is also keyed a pinion 28. The pinion 28 meshes with a gear 29 keyed to a shaft 30, to which is also keyed a pinion 31. The pinion 31 meshes with a 15 gear 32 rigidly connected with the main spring arbor 33 of the timepiece.

A plate 34 is provided to which is pivoted at 35 a pawl 36 urged into mesh with the teeth of the gear 26 by a spring 37. Thus, viewing 20 Figure 1, when the pendulum 4 moves in a clockwise direction about its pivot 3, the pawl 24 rides over the teeth of the gear 22. On the return movement, however, the pawl 24, 25 acting against the teeth of the gear 22, operates to rotate such gear in the manner of a ratchet. Thus, upon oscillation of the pendulum, the gear 22 is positively moved intermittently in a counter-clockwise direction about its pivot 3. This counter-clockwise 30 movement of the gear 22 causes clockwise movement of the gear 26. The pawl 36 prevents retrograde movement of the gears 22 and 26.

A main spring 38 is connected in the usual 35 manner with the arbor 33, so that clockwise movement of the arbor, such as will be imparted to it by oscillation of the pendulum acting through the train of gears above described, will cause winding of the spring. 40 The spring is connected in the usual manner with a barrel 39 having integral therewith a gear 40. The tension of the spring urges the barrel in a clockwise direction, viewing Figures 1 and 2. The gear 40 meshes with a 45 gear (not shown) keyed to the post 10 for rotating the hands of the timepiece.

Pivoted to the main spring barrel 39 at 41 is a modified Geneva wheel 42. The main spring arbor 33 has a vertically hollowed-out 50 portion 43 and is provided with an outwardly-projecting pin 44. The Geneva wheel 42 has three teeth 45, 46 and 47, respectively. Each of these teeth has a hollow periphery adapted to lie against the surface of the arbor 55. Normally, rotation of the arbor has no effect on the Geneva wheel, but when the pin 44 enters the cavity between adjacent teeth of the wheel, it causes counter-clockwise movement thereof during the time the pin is 60 in engagement with a tooth of the wheel, so that the Geneva wheel advances one tooth for every revolution of the arbor.

The Geneva wheel 42 is provided with an inclined cam surface 48 for a purpose to be 65 presently described. Surrounding the arbor

33 is a collar 49 having a tapered undersurface 50. Fastened to the frame at 51 and loosely embracing the arbor 33 above the collar 49 is a spring lever 52 having an upstanding stop 53 at its outer extremity. The spring lever 52 does not contact with the arbor, but has a hole in it larger than the arbor, so that the arbor passes freely through the hole in the spring lever. The collar 49, however, 70 closely embraces the arbor and is free to move axially thereof. It will be seen that axial movement of the collar 49 causes movement of the spring lever 52 so as to change the elevation of the stop 53 at its extremity.

Pivoted to the pendulum 4 at 54 is a catch 55 having a curved arm 56 provided with a series of detents 57. The catch 55 is also provided with a short arm 58 against which bears a spring 59, thus urging the catch in a counter-clockwise direction about its pivot 54. Movement of the catch, however, is limited by a stop pin 60 at the opposite side of the arm 58. The stop 53 on the spring lever 52 is so positioned that when it is raised by axial movement of the collar 49 with respect to the arbor 33, the stop will engage one of the detents 57 in the curved arm 56 of the catch, thereby stopping the pendulum.

The operation of the mechanism above described is as follows: Due to the movement of the body of the wearer of the timepiece, the pendulum 4 is oscillated about its pivot 3. This oscillation, as explained, causes intermittent counter-clockwise movement of the gear 22, which movement is imparted through the gear train to the main spring arbor 33.

When the timepiece is fairly well run down, the parts will be substantially in the position shown in Figures 1 and 2. Continued oscillation of the pendulum causes continued clockwise rotation of the arbor and, consequently, of the pin 44. This movement of the pin 44 causes rotation of the Geneva wheel 42 through one tooth for every revolution of the arbor, as above explained. When the spring is becoming fairly well wound, the pin 44 will be between the tooth 47 of the Geneva wheel and the cam portion 48 thereof. Further rotation of the arbor brings the cam portion 48 into contact with the tapered lower surface 50 of the collar 49, thereby raising such collar axially of the arbor and, consequently, also raising the spring lever 52 and bringing the stop 53 closer to the catch 55. When the spring is completely wound, the stop 53 engages one of the detents 57 of the catch 55, thereby locking the pendulum and preventing further winding of the timepiece until it has run down sufficiently for the stop 53 to become disengaged with the detent 57, 100 as will be presently described.

The catch 55 is provided with a series of detents 57 so that one of such detents will engage with the stop 53 when the stop is in its upper position, even though the pendulum 105

may not oscillate through its entire range. During certain movements of the body of the wearer, the pendulum may oscillate through only a portion of its range, which might have 5 the effect of over-winding the spring if continued for any appreciable period, unless some means were provided for stopping such part-oscillations. By reason of the provision of a series of detents on the catch 55, the 10 pendulum is locked even though its oscillation be only through a very small portion of its range.

As above mentioned, the tension of the spring 38 causes clockwise movement of the barrel 39 and, consequently, the gear 40, viewing Figures 1 and 2. When the pendulum is locked, such clockwise movement of the barrel will occur while the arbor is not rotating. The effect of this movement is to cause the 20 disengagement of the cam surface 48 on the Geneva wheel 42 with the collar 49, thereby freeing the pendulum for further oscillation.

While I have shown and described a present preferred embodiment of the invention, it is to be distinctly understood that the same is not limited thereto, but may be otherwise variously embodied within the scope of the following claims.

I claim:

30 1. In a self-winding timepiece, a case, a pendulum oscillatably mounted therein, the pendulum having anti-friction rollers for cooperation with the case, and winding means connected with the pendulum.

35 2. In a self-winding timepiece, a case, a pendulum oscillatably mounted therein, anti-friction rollers interposed between the case and the pendulum whereby direct contact between the case and the pendulum is prevented, and winding means connected with the pendulum.

40 3. In a self-winding timepiece, a case, a pendulum therein carrying anti-friction rollers whose diameter is greater than the thickness of the pendulum, and winding means connected with the pendulum.

45 4. In a self-winding timepiece, a case, a pendulum therein, a detachable closure for the case, and anti-friction means interposed between the case and the pendulum and adapted to cooperate with the detachable closure when in place.

50 5. A self-winding time piece comprising a spring, a spring barrel, an arbor, a winding means, a Geneva wheel mounted on the spring barrel and adapted to be carried around the arbor as the spring barrel rotates, a pin on the arbor adapted to engage the teeth of the Geneva wheel, the Geneva 55 wheel and the pin being fixed against relative axial movement, a cam on the Geneva wheel, and an arm extending over the spring barrel and movable toward and away from the barrel, the arm being effective by such movement for checking or freeing the wind-

ing means, the arm having a cam engaging face making direct engagement with the cam when the Geneva wheel has been turned on its axis so as to bring about such engagement.

6. A self-winding time piece comprising a spring, a spring barrel, an arbor, a winding means, a Geneva wheel mounted on the spring barrel and adapted to be carried around the arbor as the spring barrel rotates, a pin on the arbor adapted to engage the teeth of the Geneva wheel, the Geneva wheel and the pin being fixed against relative axial movement, a cam on the Geneva wheel, and an arm extending over the spring barrel and movable toward and away from the barrel, the arm being effective by such movement for checking or freeing the winding means, the arm having an opening therethrough through which the arbor extends, the arm having a cam engaging face adjacent the opening and presenting substantially the same inclination at all points around the arbor, said face making direct engagement with the cam when the Geneva wheel has been turned on its axis so as to bring about such engagement.

In testimony whereof I have hereunto set my hand.

LOUIS BURKE.
